ADJUSTMENT MECHANISM FOR WRAPPING MACHINE CROSS-FEED CONVEYERS

William Hoppe, Longmeadow, Mass., assignor to
 National Bread Wrapping Machine Company,
 Springfield, Mass., a corporation of Massa-
 chusetts

Application December 3, 1945, Serial No. 632,458

4 Claims. (Cl. 198—179)

1

This invention relates to conveyor mechanism for carrying articles such as sliced loaves of bread into accurate position relative to a wrapping machine, and in particular to improved mechanism by which the members for grasping the ends of the articles may be varied in spacing during the operation of the conveyor and either concurrently with or independently of the other adjustable parts of the wrapping machine.

The improved mechanism will be described in connection with the accompanying drawings, in which:

Fig. 1 is a top plan of the mechanism with some parts broken away;

Fig. 2 is a side elevation thereof;

Fig. 3 is a detail of the connection between the conveyor adjusting means and the control by which this means may be adjusted simultaneously with other parts of the wrapping machine;

Fig. 4 is a detail of certain chain tightening mechanism, taken on line 4—4 of Fig. 1;

Fig. 5 is a detail showing the way that centralization of the article grippers is accomplished;

Fig. 6 is a side elevation taken from the side opposite to that seen in Fig. 2;

Fig. 7 is a section on line 7—7 of Fig. 1; and

Fig. 8 is a detail of the gripper adjusting means.

The conveyor is composed of two parallel chains 1 and 2 respectively carrying reversely offset brackets 3 and 4 bearing flights or paddles 5 and 6. The brackets 3 and 4 pass up through a common slot 7 in a table 8 along which the sliced loaves are conveyed. The chains pass at one end over during sprockets 9 and 10 and at the other end over idle sprockets which have not been shown.

The drive for the conveyor is derived from a pinion 11 fixed to a shaft 12 and geared by means not shown to a suitable intermittent drive by which the conveyor chains are advanced periodically and come to rest with their pairs of paddles centralized about a fixed station such as in front of a laterally moving pusher 13. Shaft 12 has keyed to it a bevel gear 14 meshing with a bevel gear 15 keyed at 16 to a laterally extending shaft 17. A gear 18 is secured to the hub of bevel gear 15 and meshes with a gear 19 rotatable on a lateral stub shaft 20 and having a sprocket 21 secured to its hub as by screws 22. The sprockets 9 and 10 are mounted on casing members 23 and 24 collectively forming a housing for a different gearing. The casing members are freely rotatable on the shaft 17, and have bevel gears 25 and 26 secured to their inner

2

faces as by screws 27. A spider 28 having a plurality of stub shafts 29 is keyed to shaft 17 at 30. Each stub shaft has a bevel pinion 31 mounted upon it for free rotation, each pinion meshing with both bevel gears 25, 26. The spider thus serves as a driving connection between the shaft 17 and the sprockets 9, 10 while permitting relative adjustment of the latter.

If the shaft 17 be considered fixed and casing 10 24 is rotated slightly the pinions 31 will be turned, causing casing 23 to rotate an equal amount in the opposite direction. As the casings carry the chain-driving sprockets 9 and 10 the result of this motion will be to shift the two chains in opposite directions so that the pairs of flights carried by the chains will be caused to approach or separate according to the direction in which casing 24 was turned. If the shaft and casing 24 are both in rotation at the same rate a similar effect will be produced by rotating the casing a slight amount forward or back on the shaft, so that by the provision of mechanism for relatively shifting the casing and shaft while in motion the spacing of the conveyor flights can be 20 adjusted while the machine is in operation.

For this purpose the sprocket 21 is connected by a chain 32 with a sprocket 33 coupled to casing 24 as by screws 34. The sprockets 21 and 33 have the same ratios of pitch diameters as the gears 30 19 and 18 with which they are respectively coupled, so that casing 24 will be driven at the same speed and in the same direction as shaft 17. The chain does not pass directly between the sprockets, but as best shown in Fig. 8, passes over idler sprockets 35, 36 on a rocker 37. The rocker is pivoted at 38 to a support 39 having a tongue and groove connection 40 (Fig. 4) with a portion 41 of the frame. It is held in place by bolts 42 passing through slots 43 (Fig. 1) in the frame and threaded into the support. A bolt 44 passes freely through a portion 45 of the frame and is threaded into the support so that, if bolts 42 are loosened, the support may be shifted to keep the chain taut. The upper part of the rocker is formed as a segmental gear 46 engaging a worm 47 on a short shaft 48. A gear 49 attached to the worm meshes with a gear 50 on a shaft 51. As the rocker is tilted one way or the other the chain will be shifted in position so as to turn sprocket 33. The angular relation between the casing 24 and shaft 17 can thus be varied even during their intermittent rotation.

This shaft 51 extends to a place convenient for manual adjustment during operation of the machine. It is shown as passing freely through a

sleeve 52 (Fig. 3) rotatable in a portion 53 of the frame and having a sprocket 54 formed on its inner side. A collar 55 secured to shaft 51 engages the sprocket to hold it in position. The outer end of the sleeve is notched at 56 to receive prongs 57 on the hub of a handwheel 58 which is slideable on the shaft and is pressed towards the sleeve by a spring 59 compressed between the handwheel and a collar 60 secured to the shaft. The prongs 57 pass through notches in a collar 61 fast on the shaft. If the handwheel is pulled out against the spring it will engage the collar only, and can be used to adjust the shaft 51 independently of the sleeve 52. In the normal position of the handwheel the prongs connect the notched collar 61 to the sleeve, and as the latter is coupled by a chain 62 with the shaft of a handwheel 63 having chain connection 64 with various other adjustable parts of the machine (such as the folders and guides of a wrapping mechanism) the latter handwheel can be used to adjust the spacing of flights 5 and 6 simultaneously with the adjustment of these other parts. Adjustment of the flights independently is secured by pulling out and rotating handwheel 58.

One additional adjustment is provided to facilitate accurate centering of the pairs of flights 5 and 6 with respect to the rest position of the conveyor in front of the pusher 13. This is accomplished by passing the screws 27 which secure bevel gear 25 to casing 23 through arcuate slots 65 in the casing. This permits an adjustment of flights 5 independently of flights 6 as shown in Fig. 5 to secure accurate centralization, after which the spacing can be adjusted by handwheels 58 or 63.

To summarize briefly the manner in which the device operates, the main drive shaft 12 will be assumed to be in intermittent rotation. This motion is transmitted to shaft 17 through gears 14 and 15, and to the casing 24 through gears 18 and 19 and chain 32. Since the shaft and the casing are thus rotating in the same direction and at the same rate, and spider 28 is fast on the shaft, pinions 31 cannot rotate on their individual axes and therefore act to drive the casing 23 at the same speed as the shaft and casing 24. Both chains 1 and 2 travel at the same speed and the pushers of the two sets 5 and 6 remain spaced apart at a constant distance whether the chains are moving or at rest. If, however, the rocker 37 is shifted by turning either of the handwheels the chain will be pulled one way or another around sprocket 33, resulting in an angular displacement of the sprocket (and hence casing 24) relative to the shaft. This displacement causes bevel gear 26 to turn the pinions 31 on their individual axes and thus produces a rotation of casing 23 relative to the shaft an amount equal and opposite to the displacement of casing 24. The conveyor pusher pairs will thus be moved toward or away from each other an equal amount so that their centralization in rest position will not be altered.

What I claim is:

1. In a conveyor of the type having adjacent chains alternately bearing article grasping members, sprockets around which the chains pass, and a differential gearing connecting the sprockets and having a pair of gears one connected to each

5 sprocket and an intermediate gear coupling said pair of gears; adjusting and driving mechanism comprising a shaft carrying the intermediate gear for bodily rotation, a connection between the shaft and one of said sprocket-connected gears for driving it in the same direction and at the same rate as the shaft, and means interposed in said connection to displace said driven gear angularly relative to the shaft.

10 2. In a conveyor of the type having adjacent chains alternately bearing article grasping members, sprockets around which the chains pass, a differential gearing connecting the sprockets and having a pair of gears one connected to each 15 sprocket and an intermediate gear coupling said pair of gears; adjusting and driving mechanism comprising a shaft carrying the intermediate gear for bodily rotation, a driving connection between the shaft and one of the sprocket-connected gears including a chain and sprockets, one of 20 which is coupled to the latter gear, and means for varying the path of said chain to cause rotation of one of said last-named sprockets relative to the shaft.

25 3. In a conveyor of the type having adjacent chains alternately bearing article grasping members, sprockets around which the chains pass, a differential gearing connecting the sprockets and having a pair of gears one connected to each 30 sprocket and an intermediate gear coupling said pair of gears; adjusting and driving mechanism comprising a first shaft carrying the intermediate gear for bodily rotation, a driving connection between the shaft and one of the sprocket-connected gears including a second shaft parallel 35 to and driven by the first shaft, a chain and sprocket connection between the second shaft and the latter gear, a pair of idler sprockets over which said chain passes, and means for moving said idler sprockets simultaneously in opposite directions.

40 4. In a conveyor of the type having adjacent chains alternately bearing article grasping members, sprockets around which the chains pass, a differential gearing connecting the sprockets and having a pair of gears one connected to each 45 sprocket and an intermediate gear coupling said pair of gears; adjusting and driving mechanism comprising a first shaft carrying the intermediate gear for bodily rotation, a driving connection between the shaft and one of the sprocket-connected gears including a second shaft parallel to and driven by the first shaft, a chain and sprocket connection between the second shaft and the latter gear, a pair of idler sprockets over 50 which said chain passes, a pivoted rocker carrying said idler sprockets on opposite sides of its pivot, means for shifting the pivot bodily to tighten the chain, and means for tilting the rocker to 55 adjust the angular position of said latter gear relative to the shaft.

60 WILLIAM HOPPE.
